ADJUSTABLE CAP VISOR.

William H. David, Tottenville,
Staten Island, N. Y.

Application June 8, 1934, Serial No. 729,581

3 Claims. (Cl. 2—10)

The invention relates to an improvement in caps of the type which include an eye shade of transparent or translucent material or supplemental visor in addition to the usual opaque visor.

The primary object of the invention is to provide a simplified cap of the type outlined designed so that normally it will have the appearance of a cap of conventional design without visible evidence of its eye shading characteristics and which can be readily and quickly modified to dispose a supplemental visor or eye shade into operative position to form a colored transparent or translucent forwardly projecting extension to the regular visor.

Another and incidental object of the invention is to provide for the effective concealing of the supplemental visor or eye shade without providing parts especially designed for this purpose and in general to provide means for concealing the eye shade without modifying the conventional cap construction for this purpose.

Still another object of the invention is to provide a simplified means for fixedly retaining the supplemental visor or eye shade in both its concealed and in its projected operative positions.

Broadly these objects are attained simply by adding one or more snap fasteners to the usual single snap fastener at present employed for securing the forwardly extending portion of the hat crown to the portion of the fixed visor overlapped thereby and to provide a flat or arch shape eye shade or supplemental visor of crescent form in plan and made of celluloid or other material usually employed for this purpose, and by punching the same with two sets of openings, each set located to accommodate the fastening means and with the openings so located that when the fastening means engages the forward set of openings the eye shade is concealed in the pocket formed between the fixed visor and the crown, and when engaged in the other set of openings, that is, the rear set of openings, the eye shade projects forwardly in its operative position.

Various other objects and advantages of the invention will be in part obvious from an inspection of the accompanying drawing and in part will be more fully set forth in the following particular description of one form of cap embodying the invention, and the invention also consists in certain new and novel features of construction and combination of parts herein-after set forth and claimed.

In the accompanying drawing:

Fig. 1 is a plan view looking down upon a preferred embodiment of the invention and with the forward portion of the crown of the cap broken away to show in full lines the eye shade in its normal concealed position and showing in pro-

jected dotted outline the eye shade in its forwardly extending, operative position;

Fig. 2 is a view mainly in side elevation and with its forward portion showing a vertical sectional view taken on the line 2—2 through the cap shown in Fig. 1 and with the eye shade in its concealed position;

Fig. 3 is a view in plan of the eye shade detached from the cap and forming a separate article of manufacture; and

Fig. 4 is a rear edge view of the eye shade shown in the preceding figures.

In the drawing there is disclosed a cap 10 of somewhat conventional form including a crown portion 11 and a rim 12. Projecting from the forward portion of the rim is the fixed relatively rigid and opaque visor 13 overlapped by a forwardly extending portion 14 of the crown. The portion 14 forms a flat crescent-shaped pocket 15 in its overlapping engagement with the visor 13 and the portions 14 and 13 are secured at their central portions by means of snap fastener 16.

The cap distinguishes from conventional structures in the providing of two additional snap fasteners 17 and 18 positioned on opposite sides of the central fastener 16. It is herein suggested, however, that while at least two fasteners are desired in order to prevent shifting of the supplemental visor herein featured, it is within the scope of this disclosure to omit the central snap fastener 16 and to depend solely upon the outside snap fasteners 17 and 18 to secure the parts in place.

An eye shade 19 sometimes herein referred to as a second or supplemental visor as shown in Fig. 3 is crescent shape in plan, arched to conform to the usual curved form of cap visor with rounded ends 20 and having a size and configuration to fit entirely within the pocket 15 so as to be concealed from view when not in use as shown in full lines in Figs. 1 and 2. The eye shade is provided with two sets of openings, an advance set 21 adjacent the convex forward edge 23, and a second, rear set 22 adjacent the concaved rear edge 24. The openings of each set are so spaced circumferentially that the snap fasteners 16, 17, 18 are passed therethrough so as to secure the crown portion 14 to the visor 13. It is understood of the snap fasteners that one element, for instance the post element 25, is secured to and projects above the top of the visor 13 back of its forward edge 26 and its companion eye element 27 to the underside of the forwardly extending portion 14.

It will be understood that the cap can be used as such either with the eye shade entirely removed or located in the concealed position shown in full lines in Fig. 1. When it is desired to use the eye shade, the elements of the snap fasteners are separated, the portion 14 elevated thus ex-

posing the pocket 15. The shade 19 is withdrawn from its concealed position if contained in the pocket, or is taken from the coat pocket, automobile pocket, golfer's kit, or other location where it is usually contained, and located with its rear portion within the pocket, its forward edge 23 positioned to extend beyond the advance edge 26 of the fixed visor and with the elements of the snap fastener carried by the visor projecting upwardly through the set of openings 22 as shown in dotted lines in Fig. 1.

The forward portion 14 of the cap is then lowered and replaced over the rear portion of the shade and the companion elements of the snap fasteners interengaged. This will have the effect of securing the supplemental visor in its forwardly projecting position and the supplemental visor thus in effect becomes a fixed part of the fixed visor.

Should it be desired to conceal the visor when not further needed, the forward portion of the crown is elevated to separate the elements of the snap fasteners, the eye shade is lifted from its forwardly extending position and relocated rearwardly of the pocket with the fastening elements extending through the forward line of openings 21, after which the forward portion 14 of the crown is replaced, the elements of the snap fasteners again engaged and the supplemental visor is then secured out of sight and fixed in position again to form in effect a fixed part of the fixed visor.

By means of a device of this character it is possible to provide a sun shade type of cap which may be constructed economically from conventional designs as it possesses over known forms simply a couple of additional snap fasteners and a thin sheet of celluloid. The addition of the sun visor in no material way adds weight nor does it tend to distort the configuration of conventional forms of caps of the type herein disclosed. There is particularly featured the advantages of providing a cap which to all outward appearances is simply a cap of conventional design and construction but which can be easily and quickly changed to a cap which has the advantages of providing an eye shade as a structural part thereof. It is obviously within the scope of the disclosure to provide more than the two sets of openings herein disclosed to provide any desired number of adjustable positions should more than one projected position be desired. While a pin and slot form of connection is suggested to provide for adjustability in location of the visor, these slot arrangements have the disadvantage in that the slot weakens the construction of the eye shade and requires some form of clamping means to secure the visor in adjusted position, thus adding to the expense and necessitating a fastening means more cumbersome than the simple snap fasteners herein disclosed.

With the device herein described the visor is definitely fixed in both its concealed and extended positions and can be readily removed. The disclosure particularly features a construction in which the cap is maintained in its balanced and trim form as if the eye shade were not present.

While there has been shown, described and pointed out in the annexed claims, certain novel features of the invention, it will be understood that various omissions, substitutions and changes in the form and details of the device illustrated and in its operation may be made by those

skilled in the art without departing from the spirit of the invention.

I claim:

1. A cap comprising a crown and rim portion of flexible material, the crown portion including a forward projection, a fixed visor secured to the front edge of the rim, projecting forwardly therefrom, overlapped entirely by the forward projection and being relatively rigid and opaque, the fixed visor and forward projecting portion of the crown coacting to form therebetween a flat crescent-shaped pocket, a second adjustable eye-shading visor of transparent or translucent material having a similar crescent shape and of a size to fit completely in the pocket and having two operative positions, in one position contained entirely in said pocket and thus concealed from view so that the cap will appear to be of conventional construction and in the other position having its rear portion only contained in said pocket and its forward portion projecting beyond the fixed visor to form at will a transparent or translucent edge forming an eye shade extending beyond the fixed visor, means within the pocket for selectively securing the adjustable visor in its two operative positions, said means comprising two sets of openings extending through the adjustable visor with one set in advance of the other and a set of snap fasteners, one for each opening of the sets and each of said fasteners having an element thereof secured to the fixed visor and its companion secured to the forward portion of the crown and adapted to be passed selectively through its associated opening in one of the sets.

2. A cap of conventional design including a fixed visor and a crown portion overlapping the visor and forming a pocket between the visor and the part thereof overlapped by the crown portion, a plurality of circumferentially spaced and readily detachable fastening means for securing together the visor and overlapping portion of the crown and a separate eye shading visor comprising solely a thin sheet of non-opaque material having a plurality of openings one for each fastening means extending therethrough and otherwise free of fastening means, said separate visor adapted to be located with its rear edge in said pocket and its forward edge projecting beyond the fixed visor and with said fastening means passed through the openings in the separate visor to secure the visor in place without necessity of providing any fastening means in addition to the said fastening means for securing the crown portion to the visor.

3. The combination with a cap including a fixed visor and a forward crown portion overlapping the fixed visor, a plurality of spaced apart snap fasteners for securing the crown portion to the fixed visor, of a separate visor for the cap, said visor provided with two sets of openings with the opening in each set arranged in an arc, one set located in advance of the other and each set including one opening for each snap fastener, said separate eye shading visor when located with the snap fasteners engaging the forward set of openings being entirely concealed between the cap crown and fixed visor and when located with the snap fasteners engaging in the rearmost set of openings projecting forwardly beyond the fixed visor and in both positions fixedly located relative to the cap.

WILLIAM H. DAVID.
